UNITED STATES PATENT OFFICE.

GEORGE A. JOHNSON, OF CHICAGO, ILLINOIS, ASSIGNOR TO WILLIAM H. MINER, OF CHAZY, NEW YORK.

ROLLER SIDE BEARING.

1,273,868.

Specification of Letters Patent. Patented July 30, 1918.

Application filed December 6, 1916. Serial No. 135,318.

To all whom it may concern:

Be it known that I, GEORGE A. JOHNSON, a citizen of the United States, residing at Chicago, in the county of Cook and State of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

The object of the invention is to provide a relatively inexpensive roller side bearing 15 for railway cars and which is efficient in operation and composed of few parts.

In the drawing forming a part of this specification, Figure 1 is an end elevation of portions of a body and truck bolster of a 20 car showing my improvements in connection therewith. Fig. 2 is an enlarged sectional view taken substantially on the line 2—2 of Fig. 1, illustrating the side bearing proper. Fig. 3 is a sectional view of the side bearing, taken substantially on the line 3—3 of Fig. 2. And Fig. 4 is a view similar to Fig. 2 illustrating a different embodiment of the invention.

Referring to the construction illustrated 30 in Figs. 1, 2, and 3, 10 denotes a body bolster and 11 a truck bolster, the same being pivotally connected at their centers in the usual manner. As shown, the side bearing proper, which is designated generally by 35 the reference A, is attached to the upper side of the truck bolster and is adapted to cooperate with a bearing surface 12 on the underside of a body bolster.

The improved side bearing, as shown, consists of a hollow, box-like base casting having 40 a bottom wall 13, parallel side walls 14—14 and parallel end walls 15—15, the latter being provided at their upper edges with laterally extended relatively thick 45 flanges 16—16.

Mounted within the casting is an anti-friction roller 17, the latter being provided with a recess 18 extending transversely therethrough substantially at the center and 50 at right angles to the axis of the roller. Said recess 18, as clearly appears from Fig. 2, is narrow at the center and is flared upwardly and downwardly on each side, as indicated at 19—19. The recess 18 is pro-

vided to accommodate a horizontally extending steel spring plate 20, the ends of which pass through suitable slots 21 provided in said flanges 16, the slots 21 being downwardly chamfered as indicated at 22 to facilitate flexing of the spring as hereinafter 60 described. The spring is slotted at each end as indicated at 23 through which slots pass rivets 24, the slots 23 being provided to permit the spring a limited amount of longitudinal movement.

The side walls 14 of the base casting are provided with openings 25 at the bottoms thereof to permit dirt or other foreign matter to be easily washed out and in order to maintain the roller in proper position with 70 respect to the base casting, the latter is provided with a lug or tooth 26 which coöperates with a corresponding recess 27 in the lower portion of the roller.

In operation, as the two bolsters rotate 75 relatively to each other, the roller will be moved to one side or the other of its central normal position and as the roller is thus moved, it is apparent that the spring will be flexed to the general form indicated by 80 dotted lines 28 in Fig. 2, that is, with a reverse curve and fitting against the curved flaring surfaces 19 of the recess 18. Upon release of the pressure upon the roller, it is apparent that the spring will tend to 85 straighten itself and in so doing, will return the roller to central position and hold it there.

In the construction illustrated in Fig. 4, the base casting is shown as provided with 90 a bottom wall 113, parallel side walls 114, and vertical end walls 115, the latter having inturned flanges 116 at their upper ends by which the roller 117 is limited in its movements, as indicated by the dotted lines. In 95 this construction, the roller 117 is provided with a recess 118 near the bottom thereof, which recess is also flared on opposite sides of the center of the roller, as indicated at 119—119. The recess 118 accommodates a 100 horizontally extending spring steel plate 120 which extends through suitable slots 121 in the end walls of the base casting, the spring being slotted as indicated at 123 near each end to accommodate the rivets 124 and permitting a limited amount of longitudinal movement of the spring with respect to each rivet. The rivets 124 pass through inwardly 105

extended lugs 40 on the inner faces of the end walls 115 and to facilitate application of the rivets, the bottom wall 113 of the casting is recessed as indicated at 41 to permit access to the lower ends of the rivets. In this construction also, the bottom wall of the base casting is provided with a lug or tooth 126 which engages in a corresponding recess 127 formed in the bottom of the 10 roller.

The operation is substantially the same as that previously described for the structure illustrated in Figs. 1, 2 and 3.

From the preceding description, it will be 15 noted that the improved side bearing is composed of few parts which may be cheaply manufactured and easily assembled. Furthermore, the springs which pass through the rollers assist in maintaining the 20 latter in proper position and prevent the rollers from twisting with respect to the base casting, a difficulty heretofore experienced in roller side bearings where the rollers are not mounted on axles.

25 I claim:

1. In a side bearing, the combination with a hollow base casting adapted to be secured to a bolster, of a rolling member mounted therein, and means for returning said member to normal after actuation including, a 30 spring element extending through said mem-

ber at right angles to the axis of said member.

2. In a side bearing, the combination with a hollow base casting adapted to be secured 35 to a bolster, of a rolling member mounted within said casting, and a spring plate extending through said rolling member at right angles to the axis thereof and adapted to return said member to normal position 40 after each actuation.

3. In a side bearing, the combination with a base casting, of a roller mounted on said casting, said casting having end walls limiting the movement of said roller, and a 45 plate spring extending through said roller and attached at its ends to said walls, the spring being slidable to a limited extent with respect to the base casting.

4. In a roller side bearing, the combination with a hollow base casting having upstanding end walls, of a roller mounted within said base casting, said roller having a recess extending transversely therethrough, the ends of said recess being flared, and a 50 plate spring extending through said recess and slidably connected at each end thereof with the end walls of the casting.

In witness that I claim the foregoing I have hereunto subscribed my name this 4th 60 day of Dec., 1916.

GEORGE A. JOHNSON.
